SCROLL STRIPPER FOR MICROFILM CARTRIDGE

Nicholas P. Schleich, Golf, Ill., assignor to
The Matrix Corporation

Filed Mar. 9, 1970, Ser. No. 21,814

Term of patent 7 years

Int. Cl. D16—06

U.S. Cl. D61—1

FIG. 2

FIG. 1

FIG. 1 is an isometric view of a scroll stripper for microfilm cartridges showing my new design; and

FIG. 2 is a front elevational view thereof.

The rear, right side and bottom of the FIG. 1 article are substantially flat and unornamented.

I claim:

The ornamental design for a scroll stripper for microfilm cartridge, substantially as shown and described.
